(57) **CLAIM**

The ornamental design for a socket extension as shown and described.

DESCRIPTION

FIG. 1 is a rear perspective view from above of an embodiment of the claimed design;

FIG. 2 is a front perspective view from below of the claimed design of FIG. 1;

FIG. 3 is a top view of the claimed design of FIG. 1;

FIG. 4 is a bottom view of the claimed design of FIG. 1;

FIG. 5 is a right side view of the claimed design of FIG. 1;

FIG. 6 is a left side view of the claimed design of FIG. 1;

FIG. 7 is a front view of the claimed design of FIG. 1;

FIG. 8 is a rear view of the claimed design of FIG. 1;

FIG. 9 is an enlarged perspective view of the portion labeled "9" in FIG. 1;

FIG. 10 is an enlarged perspective view of the portion labeled "10" in FIG. 1;

FIG. 11 is an enlarged perspective view of the portion labeled "11" in FIG. 2;

FIG. 12 is an enlarged perspective view of the portion labeled "12" in FIG. 2;

FIG. 13 is a rear perspective view from above of another embodiment of the claimed design;

FIG. 14 is a front perspective view from below of the claimed design of FIG. 13;

FIG. 15 is a top view of the claimed design of FIG. 13;

FIG. 16 is a bottom view of the claimed design of FIG. 13;

FIG. 17 is a right side view of the claimed design of FIG. 13;

FIG. 18 is a left side view of the claimed design of FIG. 13;

FIG. 19 is a front view of the claimed design of FIG. 13;

FIG. 20 is a rear view of the claimed design of FIG. 13;

FIG. 21 is an enlarged perspective view of the portion labeled "21" in FIG. 13;

FIG. 22 is an enlarged perspective view of the portion labeled "22" in FIG. 13;

FIG. 23 is an enlarged perspective view of the portion labeled "23" in FIG. 14; and,

FIG. 24 is an enlarged perspective view of the portion labeled "24" in FIG. 14.

The ornamental design which is claimed is shown in solid lines in the drawings. The dash-dot broken lines of FIGS. 1, 2, 9-12 and FIGS. 13, 14, 21-24 depict the limits of the enlarged view and forms no part of the claimed design. The dash-dot lead lines in FIGS. 1, 2 and 13, 14 labeled 9, 10,

11, 12, 21, 22, 23, and 24 indicate the areas from which the enlargements are taken and form no part of the claimed design.
